To all whom it may concern:

Be it known that I, PHINEAS B. 10 The leading feature of my design consists of a box provided with a representation of pot-hole covers on the top and of an oven-door and fire-door at the front, the whole being a conventionalized representation of a stove.

The box is provided with a top or cover A, 15 upon which are represented pot-hole covers a.

Upon the front B of the box is represented the oven-door b, fire-door c, and ash-pit door d.

The side D of the box contains the representation of an ash-pit door e and of a drop-lid f.

What I claim is—

The design for a paper box, substantially as herein shown and described.
